UNITED STATES PATENT OFFICE

WILLIAM H. PRIESS, OF NEW YORK, N. Y., ASSIGNOR, BY MESNE ASSIGNMENTS, TO GENERAL ELECTRIC COMPANY, A CORPORATION OF NEW YORK

ELECTRIC CONDENSER AND METHOD OF MAKING IT

Application filed August 31, 1921, Serial No. 497,113. Renewed June 18, 1931.

This invention primarily relates to electrical condensers and method of making them.

The invention, however, is of general application and can be embodied in condensers of many types, among which are high potential condensers for use in radio communication, electrical power circuits and the like, and in apparatus requiring high insulation and proper arrangement of leads.

10 An object of the invention is to provide an efficient condenser having low losses.

Another object of the invention is to provide a construction whereby a high potential terminal is thoroughly insulated from parts 15 at a lower potential, and in which losses in the insulation are at a minimum.

Another object of the invention is to so construct the stack or condenser elements that, when assembled within its casing, 20 clamped and embedded, it will have and maintain the desired capacity.

Another object of the invention is to provide an improved lead and terminal.

The invention consists of the features described in detail hereinafter and illustrated 25 in the accompanying drawings, in which

Figure 1 is a sectional elevation of the assembled condenser;

Fig. 2 is an elevation thereof with parts 30 broken away; and

Figs. 3 to 5 are sectional views of modified forms of insulators.

In high potential condensers now in use, especially in condensers used in radio transmitters, it is common practice to provide a 35 metal casing which constitutes the low potential terminal of the condenser, the high potential terminal of the condenser extending through a suitable insulating cover on the casing.

In the embodiment of the invention herein illustrated, Figs. 1 and 2, I have provided such a casing 1, preferably of metal having a removable bottom or closure 2 which is 45 secured in place on the casing proper by means of screws 3 or solder, a suitable gasket 4 being interposed between the lower edge of the casing and closure 2. The closure 2, if so desired, may be flexible to yield upon expansion of the filler W of insulating material

surrounding the stack S within casing 1, when such expansion takes place. The stack S, which is under pressure, comprises alternate sheets of foil, such as lead or tinfoil, and a dielectric, such as mica. The stack S is arranged horizontally within the casing; that is, the sheets composing the stack are arranged vertically at right angles to the bottom 2, and are maintained under pressure within the casing as follows. A plate 5 is 60 placed against one of the vertical sides of the casing 1, this plate being machined and smoothed and adapted to engage one end of the condenser stack S, thereby obviating the necessity for machining and smoothing off 65 the interior of the casing 1, which is preferably cast, and may comprise aluminum or any suitable alloy of it or any other suitable metallic material. The stack S is maintained under pressure by means of a pressure 70 plate 6 arranged at the opposite end of the stack and engaged by a screw 7 threaded through the opposite wall of the casing. By adjusting screw 7, any desired pressure, of the order of thousands of pounds, may be 75 exerted upon the stack, forcing it against plate 5, the pressure plates 5 and 6 covering substantially the active area of the stack. The pressure upon stack S is of an order to maintain the sheets of foil and dielectric in 80 intimate contact free from air and voids and as nearly devoid as possible of insulating material such as paraffin. The order of magnitude of the pressure exerted in an example of a commercial form of the condenser was 85 approximately 2,200 pounds over the ends of the stack. Intermediate the top and the bottom of the casing are flanges 8 constituting securing flanges whereby the condenser may be mounted in any suitable rack.

In the embodiment of the invention herein disclosed, the stack S comprises a number of sections 9 having their foil terminals connected in series alternately at opposite ends 10 by means of solder. Between the sections 95 are located separators 11 preferably of mica. The terminals of the outermost sections or the sections at opposite ends of the stack have soldered to them copper strips or leads 12 which are bent around the ends of stack 100

S and clamped between the plates 5 and 6 respectively and the stack S, being electrically connected together through casing 1. In other words, the opposite ends of the stack 5 S are at the same potential, being electrically connected to the casing which constitutes the low potential terminal of the condenser.

In the embodiment of the invention herein disclosed, a high potential lead 13 is secured 10 to one of the foil connections 10 at the central upper portion 14 of the stack whereby the stack S is connected in series parallel; that is, the two parts of the stack, one at each side of the lead 13, are connected in parallel, 15 the individual parts comprising sections connected in series. Lead 13 is universally flexible and is a stranded wire, preferably copper; that is, a wire which is made up of a number of strands of very fine wire. The 20 inner end of the lead 13 is flared or fanned out as shown (Fig. 2) with the individual strands soldered at spaced points along the foil connection 14, whereby a very strong connection is secured between the lead 13 25 and the stack S. The fanned-out lead soldered to the foil terminal is disclosed in my co-pending application Serial No. 465,137, filed April 26, 1921, Patent No. 1,558,043, issued October 20, 1925, this present application 30 constituting a continuation in part of said co-pending application as to this feature. In constructions heretofore used, it has been found that copper strips or similar connections when connected to the foil leads, which 35 are very fragile, tend to become disconnected or torn therefrom and also tend to tear the foil terminals. By the present invention, this difficulty is obviated and strong permanent means is provided for connecting the 40 high potential lead to the stack.

Inasmuch as the high potential lead 13 must be thoroughly insulated from the casing 1, which is the low potential terminal, and in order to mount lead 13 permanently upon the 45 casing but insulated therefrom, I provide a rigid terminal such as a metal tube 15 through which the lead 13 is threaded, as illustrated, the terminal 15 being located on the casing at a point remote from closure 2. The metal 50 tube 15 projects through a suitable opening 1a in the casing 1, and is thoroughly insulated from the casing by means of an insulating device 16. In the present embodiment, this insulating device comprises a disc or plate 17, 55 of insulating material, which is of an area greater than the area of the opening 1a within the casing and extending over the boundaries of said opening. This disc is preferably of some material having high insulating 60 qualities and low loss such as mica, and should be so designed as to withstand the difference in potential between the casing 1 and the flexible lead 13 or the tube 15 through which it passes. It is preferred that this plate 17 consist of mica, which is one of the best ma-

terials for this purpose,—this plate 17 being clamped inwardly of its edge to the casing 1 by means of a metal ring 18 and screws 19 passing through the ring 18 into the casing 1, a suitable lead or 70 rubber gasket 20 being interposed between the mica sheet and the casing 1 to secure a tight joint. The tubular member 15 extends through the disc 17. Mounted around tubular member 15 below the plate 17 is a lower insulating 75 bushing 21 of reduced diameter compared to plate 17 and engaging the bottom of disc 17 and surrounding tube 15. This bushing is provided with one or more corrugations or 80 grooves 22 arranged circumferentially there- around to increase the creepage distance and consists preferably of a laminated structure; for instance a plurality of mica pieces or discs of diameter reduced compared with the disc 17 and compressed together in the manner 85 hereinafter described. Mounted around the tubular member 15 below the bushing 21 is a second or bottom insulating bushing 23, likewise of reduced diameter compared to plate 17 and preferably of some hard insulating 90 material which can be easily molded and machined such as phenolic condensation products and the like. The lower side of member 23 is provided with concentric grooves or corrugations 24, whereby the creepage distance 95 between the lead 13 and tube 15 and the condenser casing 1 is increased, and with a central recess 25 between grooves 24 adapted to receive a round nut 26 which is threaded and 100 sweated on the lower end of the member 15. The bottom bushing 23 is provided instead of mica because its flat surface, unlike mica, may be easily machined to form grooves 24 and recess 25, the bushing 23 insulating the lower 105 end of tube 15 and nut 26. Upon the opposite side of the large mica plate 17 is an upper insulating bushing 27 of reduced diameter compared with disc 17 mounted thereon and surrounding and insulating the upper portions of the member 15. Like the bushing 21, the bushing 27 is also of laminated insulating 110 material preferably built up of superimposed pieces or discs of mica and of decreasing diameter upwardly as illustrated, forming an upwardly tapering bushing.

The device 16 is preferably constructed or assembled on member 15 by assembling thereon bottom bushing 23 and the mica discs, plates or washers in their proper order from bottom to top. In the embodiment herein 115 illustrated, nut 26 is threaded on member 15 and bottom bushing 23 is placed in position, the nut 26 being thoroughly insulated by bottom bushing 23. The mica washers or pieces constituting lower bushing 21 are then 120 positioned on member 15, then insulation disc 17 is positioned and then the pieces constituting the upper bushing 27 are positioned on member 15. A washer 28 and round nut 29 are then threaded upon the upper end of 125 member 15. A washer 28 and round nut 29 are then threaded upon the upper end of 130

member 15 to hold the mica sheets and pieces in position against dislocation. The assembly of device 16 is then treated in a bath of hot molten insulating material, which will act more or less as an adhesive, for about fifteen minutes until bubbles cease, either with or without the application of vacuum. Suitable materials for this purpose are paraffin or sulfur. The assembly while hot and impregnated with molten insulating material is compressed or clamped tightly by nut 29 and allowed to cool, thus clamping the mica sheets together in a solid mass held together by nut 29 (which may be pinned to member 15) and by the fusible insulation which has now solidified. The upper bushing 27 is then cut, turned or ground to proper shape and polished, providing a smooth tapered surface 30. The bushings 21, 23 and 27 are thus retained and supported on plate 17 and held under compression entirely by means of member 15 and nuts 26 and 29. The groove 22 in lower bushing 21 is provided by assembling intermediate mica washers of reduced diameter.

Above nut 29, in close contact with the nut and member 15, is a concavo-convex metal member 31, having its concave side 32 facing the upper bushing 27 and having its edge 33 in vertical alinement with and spaced from the clamping ring 18. The inclination of the surface 30 of the bushing 27 and the curvature and spacing of the member 31 are so arranged with reference to each other and so proportioned that any difference of potential between the opposite ends of the member 15 produces electrical stresses not through the upper insulator 27 but mainly through the air from member 31 to the casing 1, maintaining the electrical field parallel with the bushing 27 instead of cutting the same. In other words, member 31 with casing 1 provides a static shield preventing losses in the insulator 16 and the destruction thereof. The member 31 also performs additional functions in that it provides a large-surfaced terminal for radiating heat generated in the stack and conducted through the lead 13 to member 31. The member 31 also serves as a protector or dust-guard for the insulating device 16, preventing deterioration thereof; that is, it is located above the insulating disc 17 and the bushing 27. The corona member 31 is secured in place by means of a nut 34 threaded upon the upper portion of the tubular member 15, and above this are located washer 35 and nut 36 whereby any suitable lead may be attached to the high potential terminal in the usual manner.

I have also provided a novel spark-gap for association with the condenser to prevent the formation of excessive differences of potential between the high and low potential portions thereof. For this purpose, the metal member 31 is struck down, forming a verti-

cal part 37, on which is mounted a round-ended spark-pin 38 having a longitudinal slot 39 therein and secured to part 37 by means of a screw and nut 40 extending through slot 39, whereby the spark-pin 38 may be adjusted vertically relative to the clamping ring 18 to increase or decrease the distance between them, the pin 38 being in vertical alinement with such ring and forming therewith a spark-gap.

Stack S of the present invention may be constructed and assembled in part in the manner described in my co-pending application Serial No. 456,903, filed March 30, 1921, Patent No. 1,652,212, issued December 13, 1927.

The process therein described covers the manufacture of a stack by preliminarily dipping the individual sheets of mica in suitable insulating material, such as paraffin, and building what is called the material stack consisting of alternate sheets of foil and dielectric, and then treating the material stack thus formed in molten insulating material such as paraffin and applying high compression and cooling, forming a solid block.

After this, the material stack is split up into sections, such as the sections 9. The projecting foil terminals are connected as at 10, and the insulating separators 11 inserted. Of course, the sections may be assembled and connected by any desired method.

For instance, each section may be built up under wax, heated, compressed and cooled under pressure. Each section is then tested for capacity and voltage. The sections are then connected in series and separators inserted between them.

After the sections have been connected by solder and the sectional separators 11 positioned, the high potential flexible lead 13 is soldered in a fanned-out manner to the intermediate connection 10, and the two low potential leads 12 are soldered to the free ends of the end sections. The stack is then placed on the base of a building stand provided with four vertical rods having vertical notches upon their inner sides adapted to receive the corners of the condensers stack; or, if so desired, a stand having six rods may be used, two rods engaging each side of the stack and one at each end.

A stand adaptable for this purpose is disclosed in a pending application of Pickard Serial No. 380,919, filed May 12, 1920, Patent No. 1,706,816, issued March 26, 1929. The stack when positioned in the stand is supported and braced by the vertical rods against dislocation and side slip. The stack and stand are then placed in a hot molten paraffin bath for approximately twenty minutes until the stack is warm, the bath being at approximately a temperature of 150° C., or in a bath of any suitable insulating material.

The stack and stand are then removed from the bath, and the stack while still in the stand and while still hot is placed under a pressure

115
120
125
130

135

of the order of magnitude of a ton per square inch over the active surface of the stack, and allowed to cool under pressure before being placed in the final condenser structure of casing 1, the vertical rods of the stand supporting and bracing the stack against side slip while under the great pressure. The stack while under the pressure of the order of magnitude above-mentioned and after 10 cooling is tested for capacity, and the capacity finally adjusted to its correct value, if this is necessary. Thus it will be seen that the final and correct capacity can be obtained before the stack is finally clamped in the casing 1 and embedded, thereby avoiding the removal of the filler after finally embedding for the purpose of obtaining desired capacity, if on test the capacity is found to be wrong. By cooling the stack under pressure 20 outside of the casing 1 in the manner above-described, the stack can also be tested for breakdown and phase angle before being placed in the casing 1 as well as measured for final length. Furthermore, by thus waxing 25 and cooling the complete condenser stack, including the separators 11, before being placed in casing 1, it can be handled as a block and side slip cannot occur during the filling operation after the stack S is placed 30 within the casing 1 and maintained under pressure by members 5 and 6.

In former processes and methods of building stacks and assembling them within the condenser casing, wax treating, compression 35 and cooling operations on the completed stack, (including the separators 11 in place, as well as the final adjustment of capacity) usually were done with the stack in a permanent clamp forming part of the condenser 40 and in the condenser casing. In that process, however, it was difficult to maintain good stacks where the length of the base exceeded by over twice the largest dimension of the stack or where sectional separators had been 45 inserted. Such length of stack by reason of the greater number of sections and the greater number of sectional separators tended to cause the side slip above referred to, upon final compression, that is, where the stack 50 was relatively high or had separators which had not previously been waxed, or both, upon compression, the elements of the stack tended to be displaced relatively to each other. By providing lateral support for the stack during compression, this difficulty is obviated.

After the stack S, including the separators 11, has been waxed and compressed, cooled and tested as above described, it is in condition to be handled, being cold and covered with wax and is directly secured within the casing 1 by means of the clamping members 5 and 6 and adjusting screw 7. The terminal gasket 20 is then positioned and the flexible lead 13 pulled up through the vertical hole through the member 15. The in-

sulator 16, including the disc 17, is then clamped to the casing 1 by means of ring 18 and screws 19. The lead 13 is then pulled up taut through member 15 and its excess length cut off. The outer end of lead 13 is then soldered to the top of member 15, which is provided at its upper end with a recess or countersunk portion 41 (Fig. 1) which fills with solder, retaining lead 13 in place and electrically connecting it to member 15. The bell 31 and remaining nuts are then assembled and spark-pin 38 properly located. This method of connecting the flexible lead from the stack S to a rigid metallic terminal is novel, inasmuch as in the present instance the soldering of this lead to the terminal is at a point outside of the casing where it is accessible and where the soldered joint can be inspected. In former constructions, the lead, usually a copper strip, was soldered to a metal terminal extending through the cover of the condenser at the lower end thereof, where it was not accessible to inspection. This soldering oftentimes has been defective, the leads becoming detached. By the present invention, however, the outer end of the lead is always placed where it can be observed and where it can easily be resoldered. Nor does this method of securing lead 13 prevent the proper manipulation of nut 36, which can be removed without interference by a soldered end 41. Furthermore, inasmuch as I have utilized in the present invention the stranded wire 13, the strands at their outer ends provide additional means for securing a very good electrical and mechanical connection with the terminal 15. After the parts have been assembled as illustrated in the drawings, with stack S held by members 5 and 6 under sufficient pressure to hold it in place, the whole condenser can be inverted, the bottom 2 being removed, and the same embedded in the manner described in my Patent 1,652,212 above-mentioned to provide a compact, non-porous, holosteric embedment W for the stack 100 and around lead 13 and terminal 15 within the condenser 1, which is free from air and voids. As described in such Patent 1,652,212, a head or extension is secured to the casing and the casing and extension are preliminarily heated by filling the same with molten paraffin at a temperature around 140° C. While thus filled, the final pressure is applied to stack S by tightening up screw 7. The molten paraffin is then removed and vacuum applied and the head and extension filled with molten paraffin or other insulating filler which is allowed to solidify in the manner described in said Patent 1,652,212. The diameter of the passage through member 15 should be such as to allow lead 13 to be pulled through while the solder at 41 makes a tight joint. In some cases, the preliminary heating with paraffin may be omitted and the stack S finally clamped under high pressure as soon as 110 115 120 125 130

- positioned. The condenser stack and terminal lead 13 are then embedded and the head and surplus wax or insulating material removed as described in said Patent 1,652,212.
- 5 After the embedment, the bottom 2, with its intervening gasket 4, is secured in place by means of the screws 3, the closure 2 being flexible, to allow the expansion of the wax, if required.
- 10 The soldering of the fanned-out stranded wire end to the foil terminal is a distinct advantage in cases of condensers having sections of low capacity; that is, having a small number of foils in a tab, because the fewer 15 foils you have the more easily the foils are torn. The connection of the lead 13 to the stud 15 at the upper end thereof is made after the stack and terminal are in place in the casing, and places the soldered joint outside the 20 casing where it can be properly made and inspected. Before the top joint is soldered, however, the lead 13 should be pulled up tight with the hand.
- The insulator 16 provided for the high potential terminal of the condenser, for the purpose of insulating such high potential terminal from the casing, provides a long creepage 25 path with short height. This increased creepage path is obtained by means of the bottom insulating bushing 23 turned with two concentric grooves 24 and machined at the center 25 to contain the lower end 26 of the high tension stud 15 whereby it is secured on the stud. Furthermore, additional creepage 30 is obtained by providing circumferential grooves in either or both of the upper and lower mica bushings 27 and 21 upon either or both sides of the mica disc 17. I have shown one such groove 22 in the mica bushing 21 below the disc 17. In the present construction, the insulator 16 comprises a single mica disc 17 clamped to the casing 1, and built-up discs of mica of reduced diameter forming bushings 27 and 21 upon and supported by the disc 17, the bushings being clamped to the disc 17 at opposite sides thereof by means of the member 15 and co-operating nuts threaded thereon. The drawings show how, in order to permit a narrow casing 45 opening, with electrical and mechanical safety, the casing and static shield (or "corona" shield as it has become known in the art), are curved or inclined with relation to one another and to the stack, so that, allowing for the necessary distance between casing parts 1 and 18 from terminal lead 15, the casing is safely remote from the portions of the stack of the higher capacities, and even so, any break-down which may occur will involve a 50 discharge from corona shield to casing in shunt to the insulating material and the stack itself, (with or without the spark-gap electrode according to the desired design). The narrow casing-opening is important because it is bridged by insulating material always

structurally weaker than metal. The invention in these respects is an improvement upon condensers of the type shown in patent to Dubilier 1,229,914 of 12 June 1917 where the cover which insulated the high potential lead from the metal casing was required in practice to be not only large in superficial area but very thick, in order to withstand the stress of a stack grown hot in service and tending to expand against the insulating cover which was one of the clamping members. In the present invention, not only is the insulating cover relieved of all functions of holding the stack under compression, but the casing-opening and therefore the insulating cover are so narrow as greatly to contribute to the practicability of the combination including the insulating cover. In the form shown, as usually in practice, the insulating cover is so narrow that it will not permit passage thru it of the stack in making the assembly, both the stack and the molten wax being inserted thru the bottom casing-opening which is made large for the purpose of readily permitting insertion of the complete stack as a whole inside the casing.

In Figs. 3, 4 and 5, I have illustrated slightly-modified forms of insulating devices 16 for use such as in condensers for insulating high potential terminals. In Fig. 3 is illustrated the large-diametered mica supporting sheet 17 clamped in the manner above described and having on opposite sides thereof the lower and upper bushings 21 and 27 as above described, of reduced diameter. In this form, however, the terminal member 15 by which the bushings 21 and 27 and disc 17 are clamped together has an integral head 15a at one end, and as here illustrated, at the outer end, and a nut 15c at the opposite end which, upon being tightened, clamps the two bushings 21 and 27 and the insulating disc 17 together between the nut 15c and head 15a. The insulator illustrated in Fig. 3 is assembled substantially like that above described, but in the reverse manner; that is, from top to bottom the mica washers or pieces constituting the upper bushing 27 are first assembled upon head 15a and finally the mica washers or pieces constituting the bushing 21. The nut 15c is then positioned and tightened up, the whole being treated and impregnated as above described. In the construction of Fig. 3, instead of utilizing nuts threaded upon the member 15 for the purpose of securing an external lead, I have provided a vertically-arranged member 15b to which the lead may be secured, this member 15b being at right angles to and integral with part 15a.

In the form of the invention illustrated in Fig. 3, the bakelite dilecto bushing 23 illustrated in Figs. 1 and 2 is omitted, and in lieu thereof I have shown the bushing 27 corrugated at 27a whereby the creepage dis-

tance is increased without materially increasing the length of the insulator. The lead 13 is secured to the terminal 15 of Fig. 3 in the manner described in connection with Figs. 1 and 2.

Referring to Fig. 4, the construction shown therein differs from the construction of Figs. 1 and 2 in the omission of the bushing 23 composed of a phenolic condensation product or other suitable plastic, and in lieu thereof the upper bushing 27 is corrugated at 27a. In other respects, the assembly is like that of Figs. 1 and 2, the nut 15c corresponding to the nut 26 of Figs. 1 and 2, directly engaging the lower bushing 21 instead of the bakelite dielecto bushing 23.

In Fig. 5, I have illustrated another form of the insulator 16 which comprises the main or large mica supporting sheet 17, which may be of any desirable configuration and secured as above described, and having on opposite sides thereof the lower and upper bushings 21 and 27 of reduced diameter and comprising laminated structures made up of sheets or pieces of mica above described. The construction of Fig. 5 differs from that of Figs. 1 and 2, however, in the provision of a high tension terminal 15 which may comprise a solid bolt upon which are threaded the mica discs, washers or pieces comprising the lower bushing 21, sheet 17 and the upper bushing 27. The inner end of the bolt or terminal 15 is provided with an integral head 15m having a transverse slot 15n therein, to which in the slot 15n the lead 13 is soldered. The parts are assembled, as above described, upon the head 15m, and thereafter the nut 29 is tightened, holding the several discs or mica washers in position upon bolt 15, tightly between head 15m and nut 29, the parts being treated with wax as above described. It should be noticed that the construction of Fig. 5 differs from the construction of Figs. 1 and 2 in the provision of a solid terminal 15 to which the lead 13 is attached at the inner end thereof instead of being threaded through the terminal 15 and soldered to the outside or outer end.

It is to be understood that the invention is not limited to the embodiments and features specifically shown and described herein, but that such embodiments and features are subject to changes and modifications without any departure from the spirit of the invention.

I claim:—

1. In an electrical condenser, a metal casing having openings at opposite ends, a member of insulating material closing one of said openings, a terminal lead extending through said insulating member, said insulating member surrounding a portion of said lead which projects outside the casing, a stack clamped within the casing and having electrical connections with the casing and stud respective-

ly, a filler of insulating material filling the casing and engaging said insulating member, and placed within the casing through the opening remote from said terminal lead, and a closure for said remote opening.

2. In an electrical condenser of the metal foil type comprising a metal casing enclosing condenser elements and having an opening for a terminal therefrom which is insulated from the casing, the improvement which comprises a tubular metal stud projecting through the casing; and a stranded conducting lead having one end extending through said stud and electrically connected to a part of the stud which is accessible from the outside of such casing, the other end of said lead having its strands separated from one another and conductively connected with a set of mutually connected foils at points located successively along the edge of the set of foils, to provide a strong connection relatively to the fragility of the foils.

3. In an electrical condenser of the metal foil type comprising a metal casing enclosing the condenser elements and having an opening for a terminal therefrom which is insulated from the casing, and having an insulating embedment in the casing around the condenser elements and terminal, the improvement which comprises a tubular terminal stud projecting through the casing; and a stranded conducting lead having one end extending through said stud and electrically connected to a part thereof which is accessible from the outside of such casing; the lead extending through said insulating embedment to the condenser elements, said end of the lead having its strands separated from one another and conductively connected with a set of mutually connected foils at points located successively along the edge of the set of foils, to provide a strong connection relatively to the fragility of the foils.

4. In an electrical condenser comprising a metal stack enclosing condenser elements and having an opening for a terminal therefrom, the improvement in supporting the terminal independently of the condenser elements and insulating it from the casing, which comprises a centrally-perforated sheet of mica mounted on the casing over its opening; an insulating material fluid when heated but solid at ordinary temperatures and compacted against the inner surface of said mica sheet; a metal annulus outside the casing arranged to secure the mica sheet thereto; a terminal stud projecting through the central perforation in the mica sheet and extending on both sides thereof in and out of the casing and having electrically connected to its inwardly projecting portion a flexible lead connected to the condenser elements within the casing, and a plurality of centrally-perforated mica sheets laterally surrounding said stud and lying adjacent thereto and

to said mica sheet, said stud projecting beyond said plurality of mica sheets.

5. In an electrical condenser comprising a metal casing enclosing the condenser elements and having an opening for a terminal therefrom which projects through said opening and is insulated from such metal casing, the improvement which comprises an insulating member supported by the casing and projecting exteriorly thereof and surrounding such terminal, and a metal bell-shaped member mounted on said terminal and having its concavity facing and extending around said insulating member and towards the metal 15 casing and electrically spaced from the latter, said insulating member extending into the concavity of the metal bell having an exterior configuration generally corresponding with the configuration of the concavity of said bell and the exterior projecting portion of said bell and insulating member having relative configurations which aid in diverting electrical stresses from the insulating member.

25. 6. In an electrical condenser comprising a metal casing enclosing the condenser elements and having an opening for a terminal lead from such elements which extends through said opening and is insulated from such casing, the improvement which comprises a metal bell-shaped member supported by such terminal lead outside such casing and arranged with its concavity toward the casing opening, said bell member being in good 30 contact electrically and thermally with such terminal and having a diameter of the order of that of the opening in such metal casing; said bell member being arranged to have at least a portion of its rim closer to the casing 35 than the distance between the rim of the casing opening and said terminal.

7. In an electrical condenser comprising a metal casing enclosing the condenser elements, electrically connected thereto to constitute a terminal thereof, and having an opening for another terminal thereof which extends through such opening and is insulated from such casing, the improvement which comprises a metal shield mounted on such terminal outside the casing and over the casing opening, the same being in good contact electrically and thermally with such terminal; and a spark-gap electrode mounted on said metal shield and spaced from the 50 metal of the casing to constitute a spark-gap between the metal shield and metal casing, said electrode being located closer to the metal of the casing than is said second terminal.

60. 8. In an electrical condenser comprising a metal casing enclosing the condenser elements, electrically connected thereto to constitute a terminal thereof, and having an opening for another terminal thereof which 65 extends through such opening and is insulated

from such casing, the improvement which comprises a metal shield mounted on and electrically connected with said second terminal in position outside said casing and over the casing opening; and a metal member spaced from the metal of the casing and constituting an electrode to establish a spark-gap between said shield and casing, said electrode having a supporting connection with said shield for movement of the electrode to and from the casing independently of any such movements of said shield.

9. In a high potential capacitor of the type wherein the condenser itself is enclosed by a metal casing connected to the condenser as a terminal thereof and having an opening for the outward projection of another terminal of the enclosed condenser, the combination with such other terminal projecting a substantial distance outside of the casing beyond the metal of the casing around the casing-opening; of an insulating member closing said opening and extending around the sides of the projecting terminal beyond the metal of the casing around the opening; and a metal member located between the metal of the casing around the opening and a portion of the projecting terminal extending beyond the insulating member, said metal member extending around the projecting terminal and insulating member and being inclined between the projecting terminal and the metal of the casing around the opening, the rim of said metal member lying sufficiently close to the metal of the casing to shunt the static field substantially from the material of said insulating member, and said inclination of said metal member being sufficient to house a substantial length of the insulating member around the projecting terminal away from the casing.

10. In a high potential capacitor of the type wherein the condenser itself is enclosed by and electrically connected to a metal casing having an opening and a terminal-lead from the enclosed condenser projecting out thru said opening, the improvement which comprises, in combination with a member consisting of insulating material, perforated for projection of the terminal lead, and located between the projecting terminal and the metal casing, of a substantially bell-shaped member consisting of metal extending curvilinearly intermediate a portion of the terminal-lead lying beyond said insulating member, and the metal of the casing around said lead-opening, the rim of said bell extending closer than the projecting terminal lead to the metal of the casing and the bell thereby constituting an electrostatic and mechanical protection for the insulating material of said perforated member.

11. A high potential condenser in a metal casing formed with a top opening and connected to one terminal of the casing, a second

terminal lead projecting from a high potential portion of the condenser out thru said opening to a substantial distance from the metal of the casing; the sides of the casing 5 at their tops being inclined upwardly and inwardly to end at said casing opening at a safe distance from the high potential portions of the enclosed condenser, said inclination providing a casing-opening of short diameter; an insulating member of correspondingly short diameter closing such casing-opening and projecting substantially beyond the casing and around a substantial length of the projecting portion of said terminal lead; 10 and a corona shield extending from a position near the metal rim of the short-diametered casing opening to a portion of the projecting terminal lead beyond the projecting portion to said insulating member, said shield in such 15 arrangement having a diameter corresponding with that of the casing-opening and insulating member and being inclined from the projecting terminal and toward the metal of the casing.

12. A high potential condenser in a metal casing formed with openings in opposite walls, a terminal lead projecting out thru one of said openings from the condenser to a substantial distance from the metal of the 20 casing; the ends of the casing-walls near said terminal lead opening being inclined thereto to end at such opening at a safe distance from the high potential portions of the condenser and provide an opening too small for insertion 25 of the condenser into the casing; an insulating member of small size corresponding to and closing said such small casing-opening; and a corona shield for said insulating member, said shield being of small diameter corresponding 30 with that of said smaller casing-opening and insulating member and inclined toward the casing-wall of said opening from electrical connection with a portion of the 35 projecting terminal lead which is remote from the metal of the casing; said opposite casing-opening being sufficiently large for insertion 40 of the condenser in the casing.

13. In a high potential condenser, the combination with a series-sectional stack, of a metal casing therefor connected with a terminal 45 thereof and formed with an opening, a terminal-lead projecting from a portion of the stack at high potential difference from the casing and out thru said opening to a suitable distance from the metal of the casing; 50 an insulating member closing said opening and projecting outside the casing and extending around the projecting portion of the terminal-lead outside the casing; and a metal static shield extending around the sides of the projection portion of said insulating member electrically connected with a portion of said projecting terminal lead, and forming 55 an electrode of an air-gap between itself and the metal of the casing, said gap being

shorter than the distance between the metal of the casing and the portion of the shield to which said terminal-lead is connected.

14. The improvement on the type of high potential condenser wherein the stack was clamped in a metal casing by a cover of insulating material and wherein the stack was connected to the casing as one terminal and the other such terminal was a lead extending out centrally thru such insulating clamping cover, said improvement consisting in causing the stack to be clamped between the sides of the metal casing itself thereby reducing the necessary thickness of the insulating cover necessary as a mechanical clamping element; and further, in combination, causing the sides of the metal casing to be inclined toward the central projecting terminal-lead without unduly approaching an end or the portion of the stack to which said lead is connected thereby reducing the width of the casing opening for said lead and reducing the superficial diameter of the insulating cover necessary when the casing sides are straight or inclined away from the central projecting terminal-lead. 75

15. The combination with a high potential condenser stack, of an enclosing casing of metal therefor connected with a terminal of said stack and having an opening opposite an intermediate portion of said stack, a second terminal of said stack projecting outside the casing thru said opening, an insulating member closing said opening and also projecting outwardly beyond said opening around the projecting portion of said terminal; and a bell-shaped member of metal located beyond said projecting portion of said insulating member, concave to the casing and extending conductively from a portion of said projecting terminal beyond the projecting portion of said insulating member to a position in space which is closer than said terminal to the metal of the casing; the bell-shaped member being arranged for enclosing a correspondingly greater length of the insulating member around the projecting portion of the terminal, and constituting the more a mechanical protection for the material of the insulating member. 95

16. A high potential capacitor comprising a stack of capacitor elements, a metal casing enclosing and holding said stack under pressure and provided with an opening on one side through which said stack is inserted, means for closing said opening, the opposite end of said casing being provided with a smaller opening smaller than the stack dimensions, a terminal connection for said stack passing through the smaller opening, the opposite stack terminal being connected to the casing, an insulating member closing said smaller opening and extending around said terminal connection beyond said casing, the walls of said casing between said smaller 100 105 110 115 120 125

- 5 16. In an electrical condenser, a metallic casting-casting formed with opposite openings and the adjacent portion of the stack sloping inwardly toward said smaller opening and terminal connection and away from said stack at a safe distance and being flattened around said smaller opening, and a fusible insulating material filling the casing surrounding the stack and contacting with said insulating closure for said smaller opening.
- 10 17. A high potential capacitor comprising a metal casing, a stack of capacitor elements therein electrically connected at one end to said casing, the casing having an opening on one side of a size too small for insertion 15 of said stack therethrough, and the walls of said casing engaging and compressing the stack-ends and being strong enough to withstand the pressure on said stack, a terminal conductor connected to said stack and passing out of the casing through said small opening, an insulating member closing said opening and projecting beyond said casing around said terminal conductor, means for opening the casing for insertion of said stack,
- 20 25 a fusible insulating material surrounding said stack and filling said casing, at least two opposite walls of the casing being provided with integral extensions which are arched about the stack toward said small opening for supporting said terminal conductor, the spacing between said stack and at least a portion of the arched extensions increasing with increase in the potential gradient between the stack elements and casing.
- 30 35 18. In an electrical condenser, a metallic casting-casting formed with opposite openings, a condenser member therein located between said openings and the casing walls; an insulating embedment-casting in the casing and around the encased condenser member; one of said openings being sufficiently large for introduction of the condenser member therethru into the casing; a lead connected to the encased condenser member and extending thru the other and opposite opening to a substantial distance outside of and beyond the metal of the casing; and a cover of structural insulating material closing said other opening, secured to the casing and extending around said lead insulating it from the casing and extending a substantial distance beyond the metal of the casing providing a long creepage path between the casing and the lead outside the casing, whereby the casing-opening for the lead is relatively small; the combination of the metallic casing, insulating cover and said lead constituting, when the condenser member is in place inside the casing, a mold for the embedment-casting between the casing and the condenser member which it encloses.
- 40 45 50 55 19. In an electrical condenser, a metallic casting-casting formed with opposite openings; a condenser stack encased thereby and arranged with its ends facing opposite closed walls of the casing and its opposite sides facing said opposite openings; means clamping said stack ends between said closed casing walls and tending to force said walls apart; one of said openings being sufficiently large for introduction of said condenser member therethru into the casing; a lead connected to the encased condenser member and extending thru the other and opposite opening to a substantial distance outside of and beyond the metal of the casing, said lead being centrally disposed with respect to the interior of the casing and said lead-opening; and a cover of structural insulating material closing said lead-opening, secured to the casing and extending around said lead insulating it from the casing and

extending a substantial distance beyond the casing in a form arched toward the portion of the lead more remote from the casing providing a long creepage path between the casing and the lead whereby the lead-opening is relatively small; the metallic casing itself also having a form arched from its wider main portion to said smaller lead-opening and generally conforming with the potential 10 gradient of the condenser member and centrally disposed lead.

22. In an electrical condenser, a metallic casing-casting formed with top and bottom openings; a condenser member encased there- 15 by and located between said casing-openings and casing-walls; an insulating embedment-casting in the casing and around the encased condenser member and between it and the casing walls; said bottom casing-opening 20 being sufficiently large for introduction of the condenser member therethru into the casing; a lead connected to the encased condenser member and extending thru the top opening to a substantial distance outside of 25 and beyond the metal of the casing; and a cover of structural insulating material secured to the casing around said lead-opening closing the same and surrounding the lead and extending a substantial distance beyond 30 the metal of the casing providing a long creepage path between the casing and the lead whereby the lead-opening is smaller than the enclosed condenser-member; the combination of the casing, the insulating cover and the 35 lead extending thru the cover constituting a closed mold for the insulating embedment-casting between the casing and the condenser-member which it encloses.

23. In an electrical condenser, a box-like 40 metallic casing, a condenser-member enclosed therein, the casing being formed with an opening sufficiently large for the introduction of the condenser member therethru into the casing; an insulating embedment-casting in- 45 side the casing and around the encased condenser-member; said casing being formed with a relatively small lead-opening opposite said larger opening and smaller than the enclosed condenser member; a lead extending 50 from the encased condenser member and out of the casing thru said lead-opening; and an insulator surrounding said lead and closing said lead-opening; said casing, insulator and lead constituting a closed mold for the in- 55 sulating embedment-casting.

24. In an electrical condenser, a box-like 60 metallic casing formed with opposite large and small openings; a condenser-member enclosed therein, and arranged with its ends 65 facing opposite closed walls of the casing and a side facing the larger casing-opening; an insulating embedment-casting in the casing and around the condenser member; a lead from the enclosed condenser-member extending out of the casing thru its smaller opening,

said lead and insulator closing the wall of the casing in which said smaller opening is formed; the larger casing-opening being sufficiently large for the introduction of the condenser-member therethru into the casing, and the assembly of the lead, lead-insulator and casing with large opening constituting a closed mold for said insulating embedment-casting.

25. In an electrical condenser, a box-like 75 metallic casing formed with a large bottom-opening and a relatively small top lead-opening, a condenser member encased thereby and arranged with its ends facing opposite closed walls of the casing and its sides fac- 80 ing the casing-walls formed with said openings; an insulating embedment-casting in the casing and around the condenser-member; a lead from the encased condenser member and extending out of the casing thru the smaller top lead-opening, said lead and insulator closing the top of the casing; the larger bottom-opening being sufficiently large for the introduction of the condenser member there- 85 thru into the casing, and the assembly of the lead, top lead-insulator and casing with large bottom-opening constituting a closed mold for said insulating embedment-casting. 90

26. In a high potential electrical condenser, a metallic casing-casting formed with opposite large and small openings, a series- 95 sectional high potential condenser stack en- cased thereby and arranged with its ends fac- ing opposite closed casing walls and its sides facing said opposite openings; means clamp- ing said stack-ends between said closed cas- ing-walls and tending to force said walls apart; one of said casing-openings being sufficiently large for the introduction of the condenser-stack therethru into the casing; an insulating embedment-casting in the cas- 100 ing around the condenser stack; a lead con- nected to said enclosed stack and extending thru the smaller casing-opening and outside the casing to a substantial distance beyond the metal thereof; and a cover of structural insulating material extending around said lead, secured to the casing around said lead- opening and closing the same, and extending a substantial distance outside the casing be- 105 yond the metal thereof providing a long creepage path between the latter and the pro- jecting portion of the lead and providing for a lead-opening smaller than the condenser- stack; said lead being disposed centrally of the lead-opening of the casing, and the cas- 110 ing having an arched formation between the lead-opening and the main casing-portion and imparting substantial rigidity to the cas- ing resisting the tendency of said clamping means to force apart the closed casing-walls between which the stack is compressed; said arched casing-portion generally conforming to the potential gradient of the condenser stack and centrally disposed lead; and the

assembly of metallic casing, insulating cover and said lead constituting, when the condenser stack is clamped in place inside the casing, a mold for said insulating embed-
ment-casting.

27. In a high potential condenser, a metallic casing-casting formed with opposite large and small openings, a condenser-member encased thereby, said larger casing-opening being sufficiently large for the introduction of the condenser member therethru into the casing; a lead extending from the condenser member thru the smaller casing-opening and extending a substantial distance outside the casing beyond the metal thereof; a casing-cover of structural insulating material secured to the casing, extending around said lead and closing the lead-opening; and an insulating embedment-casting inside the casing covering the surfaces of said insulating cover which face the interior of the casing thereby eliminating interior creepage surfaces along short distances between the metallic casing and the lead; the insulating cover extending a substantial distance outside and beyond the casing and around the projecting lead constituting a long exterior creepage path between the metallic casing and the lead; and the assembly of the lead, casing and insulating cover secured thereto and closing the lead-opening, constituting a closed mold for said embedment-casting providing access for the latter to the interior surfaces of the insulating cover.

35 28. In an electrical condenser, a metallic casing-casting formed with opposite large and small openings, a condenser-member encased thereby said larger casing-opening being sufficiently large for the introduction of the condenser-member therethru into the casing; a lead extending from the condenser member thru the smaller casing opening and extending a substantial distance outside the casing beyond the metal thereof; a casing-cover of structural insulating material secured to the casing, extending around said lead and closing the lead-opening of the casing; an insulating embedment-casting inside the casing covering the surfaces of said insulating cover which face the interior of the casing thereby eliminating interior creepage surfaces along short distances between the metallic casing and the lead; the insulating cover extending a substantial distance outside and beyond the casing around the projecting lead constituting a long exterior creepage path between the metallic casing and the lead; and a metallic static shield electrically connected and secured to a portion of the lead lying beyond the insulating cover and surrounding the lead and desirably spaced from the metal of the casing; the assembly of the lead, casing and insulating cover secured thereto and closing the lead-opening, con-

stituting a closed mold for said embedment-casting providing access of the embedding material thru the larger casing-opening to the interior surfaces of the insulating cover.
